UNITED STATES PATENT OFFICE.

THOMAS J. McNAMARA, JR., AND GEORGE KRUMMEN, OF CINCINNATI, OHIO,
ASSIGNORS TO THE PHOENIX CARRIAGE CO., OF CINCINNATI, OHIO, A
CORPORATION OF OHIO.

ADJUSTABLE BACK FOR CUSHION-SEATS.

No. 855,656.

Specification of Letters Patent.

Patented June 4, 1907.

Application filed March 11, 1907. Serial No. 361,648.

To all whom it may concern:

Be it known that we, THOMAS J. McNAMARA, Jr., and GEORGE KRUMMEN, both citizens of the United States of America, and residents of Cincinnati, county of Hamilton, State of Ohio, have invented certain new and useful Improvements in Adjustable Backs for Cushion-Seats, of which the following is a specification.

Our invention relates to adjustable seat-backs adapted for use in connection with carriage and other similar seats. One of its objects is to provide simple and reliable means by which the outline of the cushion or upholstered back may be changed at will to afford changes of position in order to rest an occupant's back.

Another object is to provide simple and efficient means for imparting a yielding movement to the parts which serve to distract the back.

It further consists in certain details of form, combination and arrangement, all of which will be more fully set forth in the description of the accompanying drawings, in which,

Figure 1 is a side elevation of a buggy-seat partly in section, embodying my improvements, and showing the back in its retracted position. Fig. 2 is a similar view showing the position of the parts when the back is in its distended position. Fig. 3 is an end view of the back-frame with the cushion removed, showing our improved mechanism to retract the cushions attached thereto. Fig. 4 is a cross or horizontal section through the back, showing a modified form of the mechanism illustrated in Fig. 1, in position to extend the back. Fig. 5 is a front elevation of the yoke-frame and end pieces shown in Fig. 4. Fig. 6 is a view similar to Fig. 4 showing a modification in which the back-extending mechanism is yieldingly held in position.

In the accompanying drawings, A, represents the carriage seat frame, and B, the back-frame to which the upholstered back, C, is attached. The upholstery preferably comprises a leather or other exterior surface material, c, a cushion of curled hair or similar material, c', and a backing diaphragm, c'', preferably of strong burlap, between which and the frame, B, is located the mechanism for changing the contour of the cushions.

This mechanism comprises a yoke-shaped bar, D, the ends, d⁴, of which are journaled in brackets, E, attached at opposite sides to the frame, B. As shown in Fig. 3, the yoke-frame, D, is flattened at d, and to its face is attached a rounded facing strip, d', preferably of wood. One end of the yoke-frame is extended out of the cushion, being provided with a rectangular seat, d², to receive an operating lever, d³.

In the positions shown in Figs. 1 and 3, the central portion, d, of the yoke-frame lies close against the back-frame, B, occupying but little space and the cushion, C, is nearly flat and also lies close against the back-frame, B.

When it is desired to have a curved or full-cushioned back, the lever, d³, is turned through an angle of ninety degrees from the position shown in Fig. 1, which causes the yoke-frame to turn in its bearings, E, thereby swinging the central portion, d, of the yoke-frame outward at right angles to the frame, B. This in turn forces the cushion, C, away from the frame, B, and burlap, c'', which is secured at top and bottom to frame, B, is held tight at the center across the facing strip, d', of yoke, D, thereby holding the cushion, C, in the desired position.

In the modification shown in Figs. 4 and 5, the yoke-frame, F, is constructed of two metal end pieces, f, f', which seat in the brackets, E, of frame, B. These end pieces f, f', are attached at f², f³, to opposite ends of a wooden cross bar, F', which is wide enough to act in the same manner as the frame, D, the end pieces, f, f', being attached at one edge of the bar, F', so that its other or projecting edge will serve when in the position shown in Fig. 4, to extend the cushion, while when turned to the other position, the bar, F', will lie close against the back-frame, B.

In the modification shown in Fig. 6, the end pieces, h, h', journal in brackets, E, of frame, B, and are provided at their inner ends with sockets in which are seated the ends, h², h³, of the yoke-frame, H. h⁴, h⁵, represent nuts or collars to retain the ends, h², h³, in their respective sockets, and h⁶, h⁷, represent springs coiled around the ends of yoke-frame, H, so that when the cushion, C, is extended by said yoke-frame, the yoke-

frame, H, will yield to pressure against the cushion by reason of the springs, h^6 , h^7 , and the sliding of the ends, h^2 , h^3 , in their respective sockets in end pieces, h , h' .

5 The mechanism herein illustrated and described is capable of considerable modification without departing from the principle of our invention.

Having described our invention, what we 10 claim is:

1. In an article of the character indicated a back-frame, a cushion attached to the edges of said frame, and a yoke-frame interposed between said back-frame and cushion, 15 said yoke-frame being pivotally attached to the back-frame and adapted to be shifted so as to lie close against the back-frame, or to be extended therefrom to alter the shape of the cushion.
2. In an article of the character indicated in combination with a back-frame and cushion, a yoke-frame interposed between said cushion and back-frame, said yoke-frame being pivotally attached to said back- 20

frame and adapted to be shifted to varying 25 positions relative thereto to alter the shape of the cushions and an exteriorly located shifting lever.

3. In an article of the character indicated in combination with a back-frame a flexible 30 cushion attached thereto at its edges, a yoke-frame interposed between said back-frame and cushion, said yoke-frame being pivotally attached to the back-frame and provided with a shifting lever.

4. In an article of the character indicated in combination with a back-frame and a cushion attached together at their edges, a yoke-frame interposed between said cushion and back-frame and pivotally attached to 40 said back-frame, the central portion of said yoke-frame being yieldingly supported relative to its pivots.

THOS. J. McNAMARA, JR.
GEORGE KRUMMEN.
